UNITED STATES PATENT OFFICE

149,537

DESIGN FOR A TEXTILE FABRIC OR SIMILAR ARTICLE OF MANUFACTURE

Augusta K. Bartholomew, New York, N. Y., assignor to Chicopee Sales Corporation, a corporation of New York

Application May 10, 1946, Serial No. 129,558

Term of patent 14 years

(Cl. D92—1)

To all whom it may concern:

Be it known that I, Augusta K. Bartholomew, a citizen of the United States, residing in New York, in the county of New York, State of New York, have invented a new, original, and ornamental Design for a Textile Fabric or Similar Article of Manufacture, of which the following is a specification, reference being had to the accompanying drawing, forming part thereof.

The figure is a plan view of a textile fabric or similar article of manufacture, showing my new design.

The design consists of a repeated unit. The unit is shown between the dotted lines in the drawing and is repeated indefinitely along one edge of the textile fabric as indicated by the extensions in the drawing beyond the unit boundaries.

I claim:

The ornamental design for a textile fabric or similar article of manufacture, as shown and described.

AUGUSTA K. BARTHOLOMEW.
